UNITED STATES PATENT OFFICE.

WILLIAM LEROY ALLEE, OF TOPEKA, KANSAS.

TOY GUN.

1,310,317.

Specification of Letters Patent. Patented July 15, 1919.

Application filed March 29, 1919. Serial No. 286,216.

To all whom it may concern:

Be it known that I, WILLIAM LEROY ALLEE, a citizen of the United States, residing at Topeka, in the county of Shawnee and State of Kansas, have invented new and useful Improvements in Toy Guns, of which the following is a specification.

This invention relates to a toy gun, and the principal object of the invention is to provide mechanism operated by a crank to feed balls into the barrel from a magazine and to project the balls from said barrel.

Another object of the invention is to provide a wheeled base for the gun having a rearwardly projecting part upon which the child may sit to propel the gun along with his feet.

The invention also consists in certain other features of construction and in the combination and arrangement of the several parts, to be hereinafter fully described, illustrated in the accompanying drawings and specifically pointed out in the appended claims.

25 In describing my invention in detail, reference will be had to the accompanying drawings wherein like characters denote like or corresponding parts throughout the several views, and in which:—

30 Fig. 1 is a side view of the invention.

Fig. 2 is a like view of the other side.

Fig. 3 is an enlarged view with parts omitted showing the crank operated means.

Fig. 4 is a plan with parts broken away.

35 Fig. 5 is a part sectional view.

In these views, 1 indicates a platform provided with the wheels 2 so that the same may be pushed along by a child sitting on the rear part of the platform. The gun is connected with the front part of the platform and said gun consists of a base 3 formed by an inclined block having its lower edge secured to the platform. The upper edge of said block has formed therewith or 40 secured thereto an extension 4, the upper edge of which is provided with a groove to receive the gun barrel 5. This barrel is firmly held in the groove by any suitable means. A small block 6 is secured to the 45 upper rear edge of the base 3, with its upper end projecting above the groove and the rear end of the barrel bears against this projecting part and is secured thereto. The gun is provided with the usual spring plunger 7 and at one side the barrel is provided

5 with a slot 8, through which projects an arm 9 connected with the rear end of the plunger and adapted to engage the means for retracting the plunger into firing position.

These means consist of a pair of spaced rollers 10 journaled to one side of the base and receiving an endless belt 11, which carry a number of wedge-shaped projections 12, said projections engaging with the arm 65 to force the spring plunger rearwardly.

The belt is also provided with openings 13, which are engaged by the pins 14 projecting from the periphery of a wheel 15. This wheel is journaled to the base below the 70 lower stretch of the belt, so that its pins will engage the openings in this part of the belt and thus move the same. A cover 16 75 encloses the rollers, the belt and the pin carrying wheel and is suitably held in place on the base. The upper edge of this cover is flanged and provides a straight edge above which the arm 9 projects. A guide 17 for said arm is formed from a piece of wire having a straight part parallel with the straight 80 edge of the cover, so that said arm is caused to travel between this straight part and the straight edge of the cover. The ends of the wire are bent downwardly and engage the screws which hold the cover in place. I 85

may use these screws to provide the journals for the belt rollers. I place a block 18 on the base between the belt rollers, said block having semi-circular recesses to receive portions of said rollers. The upper and lower 90 edges of said block are straight to provide guides for the upper and lower stretches of the belt. The journal for the pin roller is formed of stiff wire and passes entirely through the block and cover and is formed at the cover end into a handle 19 by which the wheel may be rotated and at its other end said wire is bent to form a crank 20 which is engaged by a rod 21, the other end of which engages a bell crank lever 22, 100

which is pivoted to a depending frame 23, secured to the base and extension and acting to strengthen said parts. The other end of the bell crank lever is pivoted to a vertically movable plunger 24, which operates in a cylinder 25 depending from the front end of the extension 4. The cylinder is provided with a slot through which the pivot pin connecting the piston to the bell crank passes. This plunger acts to lift the balls from the 110

magazine of the gun which is formed by a longitudinally extending opening 26 formed in the extension 4, into the barrel. The balls are forced through a hole 27 which 5 connects the front end of the magazine with said barrel. One side of the extension 4 is provided with a slot 28 through which extends an arm 29, which is connected with a spring plunger in the magazine. The other 10 side of the extension adjacent the rear of the magazine is provided with a hole 30 through which the balls are placed into the magazine. This hole is covered by a hinged cap 31. The magazine is filled with balls, such as 15 marbles or the like by drawing back the magazine plunger by means of the arm 29, so as to permit the balls to enter the magazine through the hole 30. After the magazine is filled the crank handle is turned so 20 that the pins in the wheel will engage the openings in the belt to cause the same to travel along the rollers. As the belt travels along, the projections thereon will engage the arm 9 and force the same toward the 25 rear of the gun barrel so as to retract the plunger. As the plunger is moving rearwardly the plunger 24 will be forced upwardly to pass a ball from the magazine into the barrel. Upon the continued rotation 30 of the parts the wedge-shape projection will start to move downwardly over the rear roller and thus release the arm 9 so that the plunger in the barrel will spring forwardly and strike the ball and project the same from 35 the barrel. Just at the moment that the plunger in the barrel springs forward the elevator plunger is at its topmost position so as to hold the ball within the barrel in a position to be struck by the barrel plunger. 40 The elevator plunger then descends and the plunger in the magazine forces another ball upon said elevator plunger and said plunger then rises again to force the ball into the barrel just before the release of the barrel plunger. This action is kept up as long 45 as the crank handle is turned, so that the

gun will continue to shoot as long as the supply of balls holds out.

I form a receptacle 32 on the platform at one side of the base, as shown, to receive a 50 supply of balls.

What I claim is:—

1. A toy of the class described, comprising a base having an extension at its upper edge, having a groove therein, a barrel secured in 55 said groove, a magazine formed in said extension, a vertically movable plunger for forcing the balls from the magazine into the barrel, a spring controlled plunger in the barrel, an endless belt, a pair of rollers 60 for supporting said belt, projections on the belt for engaging a part of the spring plunger for retracting the same, a wheel, pins thereon engaging the belt for revolving the same, a crank handle for rotating the wheel 65 and means connecting the handle with the vertically movable plunger to operate the same.

2. A toy of the class described, comprising a base, an extension on the upper edge there- 70 of having a groove in its upper edge and a longitudinally extending opening forming a magazine, said extension also having a slot communicating with said opening, a spring-pressed plunger in said opening, an arm on 75 said plunger extending through said slot, a barrel in the groove in the extension, a vertically movable plunger for lifting the balls from the magazine into said barrel, a spring controlled plunger in said barrel, the lower 80 end of said barrel having a slot therein, an arm connected on the plunger and projecting through said slot, a pair of rollers journaled to the base, an endless belt carried by said rollers, projections on said belt adapted 85 to engage with said arm for retracting the plunger, a crank handle for rotating the belt and means for operating the vertically movable plunger by said handle.

In testimony whereof I affix my signature. 90

WILLIAM LEROY ALLEE.
